UNITED STATES PATENT OFFICE.

ORRELL ASHTON, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

SHOE-SHAPING MACHINE.

1,175,215.

Specification of Letters Patent. Patented Mar. 14, 1916.

Application filed December 12, 1913. Serial No. 806,325.

To all whom it may concern:

Be it known that I, ORRELL ASHTON, a citizen of the United States, residing at Swampscott, in the county of Essex and 5 State of Massachusetts, have invented certain Improvements in Shoe-Shaping Machines, of which the following description, in connection with the accompany drawings is a specification, like reference characters 10 on the drawings indicating like parts in the several figures.

This invention relates to the manufacture of shoes, and has particular reference to the shaping of turn shoes after the lasting, sewing, shoe turning and relasting operations 15 have been performed. These operations leave the upper and the sole in a more or less distorted and rough condition, and considerable smoothing and beating out are required 20 in order to conform the shoe accurately to the shape of the last and to impart to the upper and the sole a smooth and finished appearance. Although machines have been devised for beating out the sole, the 25 shaping operations above referred to upon turn shoes have been performed heretofore very largely by the use of hand tools.

An object of the present invention is to provide an improved machine embodying 30 mechanical devices suitable for operating upon such shoes to conform them to the shape of the last and give them the required finished appearance.

To the above end a feature of the invention 35 consists in novel and improved beating mechanism comprising a shoe beating tool, herein shown as a lever having a portion formed for engagement with a shoe, and operating means comprising preferably a 40 rotary cam arranged for sliding engagement with the tool to impart positive operative movement thereto without undue force of percussion and with reference to which the tool is in an inoperative position except 45 when moved by pressure of a shoe into position to receive its operative movement.

The invention also provides a novel and 50 convenient arrangement whereby a shoe beating lever is formed at one side of its fulcrum for engagement with a shoe and is moved by pressure of the shoe into position to receive operative movement from means engaging the lever at the other side of its fulcrum, and this arrangement constitutes 55 another feature of the invention.

A further feature of the invention consists in a shoe beating tool suitably operated to impart a series of beating impulses and formed in one portion for beating the shank of a shoe sole and in another portion for 60 beating a different part of the shoe such as the upper adjacent to the rand crease. This arrangement preferably includes also means whereby the force of the beating impulses may be varied, since a longer or heavier 65 stroke of the beater is desirable for shaping the shank of a shoe sole than for smoothing the upper.

As a further feature the invention provides an improved shank beating device 70 comprising a novel combination and arrangement of beating tool and shoe positioning means. The construction shown includes a pivoted shoe beating tool normally disposed in inoperative relation to its operating means and movable by pressure of a shoe against it into position to be operated by said means, together with shoe positioning means arranged to engage the shank of the shoe to assist the operator in guiding 75 the shoe for effective treatment by the tool and to prevent the tool from being forced into position to engage its operating means continuously, thus insuring a more positive beating effect. Conveniently also the tool 80 may be formed for beating the shoe upper by extending it beyond the shoe supporting means and providing an upper beating face on its outer end portion.

Still another feature consists in mechanism constructed and arranged for ready manipulation to vary the beating effect of a shoe beating tool, comprising preferably and as herein shown a pivoted stop arranged to limit the movement of the tool toward 90 its operating means and movable quickly to a position to secure a different range of movement of the tool. Such a device is particularly useful in connection with a combined shank and upper beating tool, such as 95 above described, since it is desirable, where both operations are to be performed in succession upon the same shoe, to change the adjustment of the beater very quickly.

These and other features of the invention, 105 including certain details of construction and combinations of parts, will now be described more fully with reference to the accompany- ing drawings and pointed out in the claims.

In the drawings, Figure 1 is a view in 110

front elevation of the upper portion of a machine embodying a preferred form of the invention, Fig. 2 is an end view of the upper shaping device shown at the right of Fig. 1, with the casing in section, Fig. 3 is an end view of an alternative form of beating device, embodying means for shaping the shank of a shoe and the sides of the shoe upper, and Fig. 4 is a section on the line 4-4 of Fig. 3.

The machine comprises a head or frame 2 supported on a standard 4 at an elevation convenient for the operator in presenting a shoe to the shaping devices. The frame has bearings for a main shaft 6 which is driven from a belt 8.

One of the shoe shaping devices in the illustrated machine comprises a drum 10 which rotates with the shaft 6 and has at its periphery several rows of shoe beating rings 14, and above the drum a beater 28 arranged to operate upon the side of the shoe simultaneously with the operation of the rings 14 upon the sole, this beater being operated by means of a shaft 16 driven by a belt 18. This device is not claimed herein, but in my copending application, Serial No. 597,190, filed December 14, 1910; and is herein shown to illustrate the type of machine of which the mechanism of this invention may conveniently form a part.

Near one end of the main shaft 6 are formed a series of cams 36 and pivoted on the frame 2 at 38 is a beater in the form of a lever 40, the rear or lower end of which is adjacent to the cams 36 and the upper end portion of which is provided with a concave shoe engaging face 42. The lever 40 is held normally out of operative relation to the cams 36 by a spring plunger 44, an adjustable stop 46 serving to limit movement of the lower end of the lever away from the cams. The beater is thus rendered operative by pressure of the work against the face 42. An adjustable stop 48 limits movement of the lever toward its cam engaging position and thus determines the amplitude of its oscillations or shoe beating movements. The beating face 42 is shaped to extend deeply into the crease between the upper and the sole for beating out and smoothing any wrinkled or uneven portion of the upper not readily reached by other beating tools.

In Fig. 3 is shown an alternative form of beating device which combines substantially the principal features of the device shown in Fig. 2 with means for beating the shank portion of the sole of the shoe. In this arrangement the shaft 6 is formed preferably with a single cam projection 50, and the beating tool or lever, which is pivoted at 52 to the frame, includes a straight shank engaging portion 54 and an upper beater 56 at the end of the tool. The beater 56 is

intended to perform substantially the same work on the shoe as the beater shown in Fig. 2, and its shoe engaging face may be shaped similarly to the face 42. The shank beater 54 has cooperating therewith rigid supporting means against which the shoe may be pressed and guided during the shank beating operation, such means comprising in the construction shown a pair of parallel supports 58 on opposite sides of the tool. 70 This supporting or positioning means prevents the shoe from forcing the tool to the limit of backward movement determined by the operating means and thus insures a more positive beating effect. The shoe beating lever has an arm 60 extending over the cam portion of the shaft 6 and normally held out of the path of the cam through the operation of the spring plunger 62, which positions the tool with its beating face projecting forwardly from the plane of the supports 58. Either portion of the beater is thus rendered operative through the pressure of the work against the respective shoe engaging face.

The means for limiting movement of the form of beater shown in Fig. 3 toward its operative position with reference to the cam 50 preferably comprises a stop member 64 which is pivotally mounted on the frame 95 and has a shoulder 66 for engaging the rear face of the lever to limit the movement of the latter when the beating portion 56 thereof is in use. When this stop is turned into the dotted line position the shoulder 66 is 100 withdrawn from the path of the lever so that the latter may be moved farther backwardly and the arm 60 swung into closer relation to its operating cam. This position corresponds to the shank beating operation of the tool where wider oscillations of the beater are desirable. For retaining the stop securely in either of its positions of adjustment there is provided a spring plunger 68 which is shaped to enter notches 110 formed in the curved portion of the stop. For securing a further adjustment of the stop the latter is mounted upon an eccentric stud 70 which is adjustable by means of its slotted head to vary the position of the shoulder 66 when the stop is in its full line position shown in Fig. 3. For limiting the forward throw of the tool a stop 72 is provided, this stop comprising preferably a yielding spring-held plunger, as shown, so 120 as to avoid possible injury or breakage of the arm 60.

In the use of the device shown in Fig. 3 the shank may be beaten by placing the shoe in the dotted line position and pressing the 125 beating tool back into operative relation to the cam, the supports 58 serving to guide and position the shoe as it is pressed backwardly and moved to present different portions of the shank to the beater. During 130

this operation the stop is thrown into the dotted line position to permit wider oscillations of the beating tool. For beating the sides of the upper the shoe is placed in the 5 full line position shown in Fig. 3, the stop being turned to present the shoulder 66 to the rear face of the beater so as to restrict the amplitude of its oscillations while performing the lighter work upon the upper 10 portion of the shoe. With the use of this device it will be clear that the beater may be adjusted instantly by the operator to beat either the upper or the bottom of the shoe so that these different portions of the shoe 15 may, if desired, be presented alternately to the respective operative portions of the tool to perform the two different operations thereon.

It will be apparent that the arrangement 20 shown and described of a pivoted beater with one arm extending rearwardly over its operating cam and its other arm forwardly inclined for engagement with a shoe permits the shoe to be presented conveniently 25 in position for treatment without interference by the operating means or other portions of the machine.

Although I have disclosed the invention as embodied in a machine having the specific 30 features of construction shown and described, it should be understood that the invention in its broader aspects is not thus restricted in its application but that other embodiments are comprehended within the 35 spirit and scope of the claims.

Having described the invention, what I claim as new and desire to secure by Letters Patent of the United States is the following:

40 1. A shoe shaping machine having, in combination, a shoe beating tool comprising a pivoted lever formed at one side of its fulcrum for engagement with a shoe, and operating means for said tool constructed 45 and arranged to engage the tool at the other side of its fulcrum, said tool being disposed normally in inoperative relation to said operating means and movable into operative relation to said means through pressure of 50 the shoe against the tool.

2. A shoe shaping machine having, in combination, a pivoted shoe beating tool formed for engagement with a shoe, operating means for said tool comprising a cam 55 rotatable adjacent to the tool and constructed and arranged for wiping engagement with the tool while swinging the tool to beat the shoe, and resilient means for holding the tool normally out of the path of 60 movement of said cam while permitting it to be moved by pressure of a shoe into position to be engaged by the cam.

3. A shoe shaping machine having, in combination, a pivoted shoe beating lever, 65 a cam for engaging one arm of said lever to

impart shoe beating movements to the lever, resilient means for holding said arm normally out of the path of movement of said cam, and a yielding stop for limiting movement of said arm in a direction away from 70 the cam.

4. A shoe shaping machine having, in combination, a shoe beating tool, means for operating said tool to beat the shoe, said tool being disposed normally in inoperative relation to said means and movable into operative relation thereto through pressure of the shoe against the tool, and a stop for limiting said movement imparted to the tool by the pressure of the shoe, said stop being 80 pivoted for turning movement out of said limiting position.

5. A shoe shaping machine having, in combination, a pivoted shoe beating lever, a cam constructed and arranged to engage said 85 lever and impart shoe beating movements thereto, said lever being disposed normally out of the path of movement of said cam and movable into operative relation to the cam through pressure of the shoe against 90 the lever, and means for adjustably limiting the movement of said lever toward the cam.

6. A shoe shaping machine having, in combination, a pivoted shoe beating lever, a cam for engaging said lever and imparting shoe beating movements thereto, said lever being disposed normally out of the path of movement of said cam and movable into operative relation to the cam through pressure of the shoe against the lever, and a stop for limiting the movement of the lever toward the cam, said stop being pivotally mounted for turning movement out of said limiting position.

7. A shoe shaping machine having, in combination, a pivoted shoe beating tool, operating means for said tool constructed and arranged to engage the tool and impart shoe beating movements thereto, said tool being disposed normally out of the path of movement of its operating means and movable into operative relation to said means through pressure of a shoe against the tool, a stop rotatable into and out of position to limit the movement of the tool toward its 110 operating means and a bearing for said stop constructed and arranged for adjustment to vary said limiting position of the stop.

8. A shoe shaping machine having, in combination, a shoe beating tool comprising a pivoted lever, means for engaging said lever and imparting shoe beating movements thereto, said lever being disposed normally out of the path of movement of its operating means and movable into operative relation to said means through pressure of the shoe against the tool, a stop for limiting the movement of said lever toward its operating means, said stop being pivoted for turning movement out of said limiting position, and 130

yielding means for retaining said stop in either its limiting or its inoperative position.

9. In a shoe shaping machine, a pivoted shoe beating tool having a shank engaging portion and a different portion shaped to lever being disposed normally out of the engage the side of a shoe and to enter the crease between the upper and the sole, means for oscillating the tool, and means for varying the amplitude of oscillation of the tool to obtain different effects respectively for shank beating and for side beating.

10. A shoe shaping machine having, in combination, a pivoted shoe beating tool, operating means for imparting forward beating movements to the tool, said tool being disposed normally out of the path of movement of its operating means and movable rearwardly into operative relation to said means through pressure of the shoe against the tool, and shoe positioning means arranged to prevent the shoe from forcing the tool to the limit of rearward movement determined by said operating means.

11. In a shoe shaping machine, shoe beating means comprising a support upon which to position the shank of a shoe, a shank beating tool at one side of said support, and means for operating said tool, said tool being formed at its outer end beyond said support with means for engaging and beating the side of the shoe.

12. A shoe shaping machine having, in combination, a pivoted shoe beating lever formed with a shank engaging portion and with a portion shaped to engage the side of a shoe, operating means comprising a cam for engaging and operating the lever, said

lever being disposed normally out of the path of movement of said cam and movable into operative relation thereto through pressure of the shoe against the lever, and a stop for limiting movement of the lever toward the cam, said stop being pivotally mounted for turning movement out of said limiting position.

13. In a shoe shaping machine, a shank beating device comprising a beating tool pivoted for oscillatory movement, means for operating the tool, and shoe positioning means comprising a pair of supports at opposite sides of the tool for engaging the shank of the shoe, the tool being disposed normally in inoperative relation to its operating means with its beating face projecting forwardly from the plane of said supports and movable by pressure of a shoe into position to be operated by said means.

14. A shoe shaping machine having, in combination, a shoe beating tool pivoted for oscillatory movement, and a rotary cam for operating said tool, the tool having an arm extending rearwardly over the cam for engagement with the cam and another arm extending upwardly and forwardly from the axis of the tool and shaped for engagement with a shoe in and adjacent to the crease between the upper and the sole as the shoe is presented bottom uppermost.

In testimony whereof I have signed my name to this specification in the presence of two subscribing witnesses.

ORRELL ASHTON.
